UNITED STATES PATENT OFFICE.

ROBERT GANS, OF BRONX, NEW YORK.

SOCKET ATTACHMENT.

Application filed June 30, 1924. Serial No. 723,414.

To all whom it may concern:

Be it known that I, ROBERT GANS, a citizen of the United States, residing at Bronx, in the county of Bronx and State of New York, have invented certain new and useful Improvements in Socket Attachments, of which the following is a specification.

This invention relates to socket attachments and more particularly to a novel and improved device adapted to be connected to the key or button of an electric light socket for operating the same with facility and ease wherever the socket may be positioned.

One of the objects of my invention is to provide a socket attachment adapted to be positioned at the side thereof and connected to the socket key or button in such manner that the latter may be rotated to close or open the circuit without interference with the reflector or globe surrounding the lamp bulb.

A further object of my invention is to provide an electric light socket attachment constructed and arranged to be conveniently mounted on different styles and types of sockets in such position that the socket key may be conveniently rotated when positioned at a point overhead so as to open and close the circuit to the bulb.

To enable others skilled in the art to fully comprehend the underlying features of my invention that they may embody the same in the various modifications in structure and relation contemplated, drawings depicting a preferred form have been annexed as a part of this disclosure and in such drawings, similar reference characters denote corresponding parts throughout all the views, of which,

Figure 1 is a view in side elevation of a socket showing my attachment in position.

Figure 2 is a side elevation partly in section of the attachment with relation to the socket.

Figure 3 is a section taken on the line 3—3 of Figure 2.

Figure 4 is a view taken on the line 4—4 of Figure 2.

Figure 5 is a modified form.

Figure 6 is a view taken substantially on the line 6—6 of Figure 5.

Referring now to the drawings wherein like reference characters designate corresponding parts throughout all the views, 5 designates a conventional type of electric light socket to which my attachment is

adapted to be connected at a point below the collar 6 and as shown in dotted lines on the illustrated drawing. My invention proper consists of a cylindrical, cup-shaped member 7, open at its inner face which is formed and shaped to engage and fit the side of the socket 5 as shown by numeral 8, see Figure 2. In the form of the invention shown by Figures 1 to 4 inclusive within the cup-shaped member 7, I provide a key or button engaging member 9 which is adapted to frictionally hold and rotate with the electric light key or button 10 which controls the operation of the bulb. The key operating member is mounted on a pin 11 within the cup-shaped member 7 and in close engagement with the closed, side wall 12. The outer face of the key operating member is serrated as at 13 and the wall 12 is provided with a segmental notch or cut out portion 14. Mounted on the pin 11 is a lever 16 having an extension or dog 17 adjacent one end thereof, which dog is adapted to engage the serrations of the key turning element so as to rotate the same when the lever is actuated. A spring 18 encircles a small sleeve 19 on the threaded portion 20 of the pin, said spring being bent inwardly one end of said spring being secured to the cup-shaped member 7 as at 21 and the opposite end of the spring, connected to the lever as at 22, it being observed that the spring performs the double function of urging the dog toward the serrated key operating member and also causes the lever to return to its normal position when actuated. A locking nut 23 and washer 24 on the pin retains the lever and sleeve in proper position. A pull chain 26 is secured to the apertured end 27 of the lever for the obvious purpose.

Riveted to the sides of the cup-shaped member 7, is a divided clamp 29, the arms of which encircle the socket just below the collar and the free ends of the clamp are secured by a threaded bolt and nut as clearly shown by Figure 4 of the drawings.

As a modified form of the invention as shown by Figure 6, the key operating member comprises a ratchet 31 formed with the key retaining portion 32 and a pivoted dog 33 cooperating with the ratchet and the pivoted lever 34, rotates the said key in the same manner as above described. A spring 35 on the pin 36 causes the lever to return to its normal position when actuated. The

cup-shaped member 37, of course, is similar in construction to the cup-shaped member 7 and the same type of clamping device or its equivalent may be resorted to for securing 5 the modified form of the attachment to the socket.

While I have illustrated and described my invention with some degree of particularity, I realize that in practice various alterations 10 therein may be made. I therefore reserve the right and privilege of changing the form of the details of construction or otherwise altering the arrangement of the correlated parts without departing from the 15 spirit of the invention or the scope of the appended claims.

Having thus described my invention what I claim as new and desire to secure by United States Letters Patent is:—

20 1. An attachment for electric lamp sockets comprising a cup-shaped member open at one end and shaped to conform to the curvature of a socket, means for clamping said member to the side of the socket, a 25 serrated, faced key operating member within the cup-shaped member, a pin extending through the closed end of the cup-shaped member, a resiliently controlled lever pivoted on said pin and means carried by the lever 30 and engaging with the serrated face of the key operating member to partially rotate the same.

2. An attachment for electric lamp sockets comprising a cup-shaped member open at 35 one end and shaped to conform to the curvature of a socket, means for clamping said member to the side of the socket, a key operating member within the cup-shaped member, the outer face of said key operating member being serrated, a pivoted lever hav-

ing a dog engaging said serrated face and a spring for urging said dog in engagement with the serrations and adapted to return the lever to its initial position, after each partial rotation of the key operating 45 member.

3. An attachment for electric lamp sockets comprising a hollow element open at one end and shaped to conform to the curvature of a lamp socket, means for clamping 50 said element to the side of the socket, a rotatable key operating member within the hollow element, a pin extending through the closed end of said element, a resiliently controlled lever mounted on said pin and a 55 dog operable in a segmental notch in the closed end of the hollow element to partially rotate the key operating element when the lever is actuated.

4. An attachment for electric lamp sockets 60 comprising a cup-shaped member open at one end and shaped to conform to the curvature of a socket, a clamping member for attaching the said cup-shaped member directly to the side of the socket, a key operating element within the cup-shaped member, said key operating member having a serrated face, the outer closed face of the cup-shaped member being slotted, a pin extending through the said outer face, a lever 65 pivoted on said pin, a dog carried by the lever and engaging the serrated face of the key operating member, and a spring mounted on said pin, one end of the spring being attached to the cup-shaped member 70 and the opposite end to the said lever.

In testimony whereof I affix my signature.

ROBERT GANS.
